PERFORATED TAPE READER

Gene D. Vedder, Granada Hills, Calif., assignor to
Ex-Cell-O Corporation, Detroit, Mich.

Filed Nov. 6, 1972, Ser. No. 304,231

Term of patent 14 years

Int. Cl. D14—02

U.S. Cl. D26—5 C

FIG. 1

FIG. 2

FIG. 3

FIG. 4

FIG. 5

FIG. 1 is a front perspective view of the perforated tape reader showing my new design;

FIG. 2 is a front elevational view thereof;

FIG. 3 is a top plan view thereof, the bottom being plain and unornamented;

FIG. 4 is a left side elevational view thereof; and

FIG. 5 is a right side elevational view thereof.

I claim:

The ornamental design for a perforated tape reader, as shown and described.
